UNITED STATES PATENT OFFICE.

GEORGE P. BENDER, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

TANK-CAR.

1,140,656.

Specification of Letters Patent. Patented May 25, 1915.

Application filed December 6, 1912. Serial No. 735,292.

To all whom it may concern:

Be it known that I, GEORGE P. BENDER, residing at Berwick, Columbia county, Pennsylvania, and being a citizen of the United States, have invented certain new and useful Improvements in Tank-Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a side elevational view partly in section illustrating the invention applied to a tank car. Fig. 2 is an enlarged fragmentary view partly in section, the section being taken on line 2—2 of Fig. 4. Fig. 3 is a transverse sectional view, section being taken on line 3—3 of Fig. 2. Fig. 4 is at the right a plan view of the details shown in Fig. 2, and at the left a transverse section, the section being taken on line 4—4 of Fig. 2. Fig. 5 illustrates in longitudinal section a modification of the device shown in the other figures, as herein-after described, and Fig. 6 is a central vertical longitudinal sectional view showing a slightly modified form of wedge suspension.

It is well known that tank cars used for transporting fluid products comprise, generally an underframe with a tank suitably mounted thereon and held in position between end head blocks or by central anchorage of some suitable type preferably including a center anchor casting or anchor depending from and riveted to the tank and suitable lugs or abutments therefor secured to the underframe of the car to prevent longitudinal shifting of the tank on the underframe, and the tank being held in position on the underframe by conventional tank bands which partly surround the tank and are anchored to the underframe.

Owing to the nature of the lading it is found quite difficult to anchor the tank in position in such manner as to prevent some slight longitudinal shifting, which shifting is considered a disadvantage.

To overcome difficulties heretofore encountered the present invention comprises an anchoring means adapted to anchor the tank of a tank car to its underframe in such manner as to prevent longitudinal shifting of the tank, and at the same time to so connect the tank to the underframe as to prevent separation in a vertical direction under normal conditions, but with the parts so disposed and so operative that when it is desired to separate the tank from the underframe this may be readily accomplished without destructive effort.

The invention applies particularly to the anchorage shown and described in Reissue Patent 12832, of July 21, 1908, issued on the application of John McE. Ames, and is in the main supplemental thereto, though in the modification shown in Fig. 5 the device departs from the principle of said Ames structure, as hereinafter more fully set forth.

Referring to the parts: 1 is a car body or tank of the conventional form provided with longitudinally extending bottom sheet 2 and mounted above the underframe, comprising center sills 3—3 with bolster 4, and short side sills 5, or not, as may be desired, no part of the underframe, except the center sills, being essential to the application of the present invention. By preference the anchor is centrally disposed relative to the length of the tank, but it may be positioned forwardly of the bolster 4 and between such bolster and the ends of the center sills; that is, between the bolsters and the couplers.

In the embodiment of the invention disclosed in the drawings in Figs. 1 to 4, inclusive, lugs or stops 6 are attached to the center sills 3, as shown in Fig. 4. These lugs span the space between the center sills, and are riveted thereto and form connections for the spaced center sills, which will effectually prevent buckling of the center sills during buffing. Depending from the tank in the figures referred to is a center anchor casting 7, which, as shown in Fig. 3, is provided with an arcuate top flange 8, conforming to the curvature of the bottom sheet 2 of the tank and is riveted securely thereto. The center anchor casting comprises spaced walls extending longitudinally between the sills 3, and between these walls the outlet valve 10 from the tank passes, as

is usual in anchors of this type, there being a clear space between the walls or spaced depending flanges 7 of the anchor casting for the passage of said outlet valve.

5 Connecting the walls 7 at each end I provide a transverse wall or end flange 12 which serves as a connector for the walls 7, adapted to coöperate with the stop which is interposed between said walls 12 and the 10 lugs 6, before referred to. The center anchor casting thus far described forms no part of the present invention but supplemental to the descri^l parts of said casting the present invention particularly applies 15 and includes an extension of said casting, as shown in the drawing.

At each end of the center anchor casting 7, shown in Figs. 1 to 4, inclusive, the part thereof depending below the flanges 8 is recessed at 13 providing at each end of the 20 anchor casting a plurality of pockets which are adapted to receive therein the square heads 14 of long bolts 15, which are held in said pockets 13 with the stems of said 25 bolts depending, the bolts being screw-threaded for a convenient distance at their lower ends and having slipped thereon the block or wedge 16, which wedge is preferably provided with a straight vertical face 30 17 where it contacts with the outer face of the end walls 12, before referred to, and is provided with an inclined face 18 at its opposite side; that is, the side of the wedge next adjacent the lug 6, before referred to, 35 so that when the wedge is moved upwardly it will contact with an inclined face of the lug 6, there^y locking the tank firmly in position, it being understood that the wedges 16 are placed, as shown in Figs. 1 to 4, inclusive, with one wedge interposed between 40 each wall 12 and the contiguous lug 6.

Adjusting nuts and lock nuts 20 and 21 are provided for well known purposes. By using the wedges in connection with the center anchor of the before referred to reissue patent, it is obvious that the tank may be more firmly locked in its position than could be with the structure disclosed in said patent. It is well known that tanks of tank 50 cars are heavy bodies which are ordinarily lifted by means of power cranes, and extreme care must be taken in placing the tank in position under normal conditions, in addition to which some clearance between the center anchor casting 7 and the stop lugs 6 is required to facilitate placement of the tank, which clearance, even though very small, sometimes permits independent movement of the tank on the underframe. When 55 the wedges 16 are used, as before described, it is evident that the tank may be placed in position with the bolts 15 merely resting in the pockets therefor and depending with the casting 7 between the stop lugs 6, after 60 65 which the wedges 16 may be placed in po-

sition and tightened so as to firmly lock the tank in a desired position.

There is a positive advantage in using the wedge of this invention, in that the rigidity of tank and underframe are assured and there is no necessity for perforating the center sills for the passage of transverse keys which have been suggested as a means for anchoring the tank on the underframe. The same feature of advantage may be secured 70 by the use of the wedge shown in Fig. 5, which is adapted to coöperate with an anchor member 7^a depending from one end of the tank, which anchor member is provided with the wall 12^a extending transversely between center sills, as 3, the wedge 16 being interposed between said wall 12^a and an extension 6^a, which is cast integral with and forms a part of the bolster center filler casting, which center filler casting is common in 80 85 the art.

An advantage of the end anchor construction disclosed in Fig. 5 over the center anchor construction shown in the other figures is that the tank is more firmly held in 90 position at the bolsters, so that rocking of the tank on its underframe is positively prevented. In the construction shown in Figs. 1 to 4, inclusive, the central tank bands B—B could be omitted, because the tank 95 and underframe are held against vertical separation by means of the interlocking of the wedge 16 with the lugs 6, while with the construction shown in Fig. 5 the end tank bands C may be omitted because the tank 100 is in that construction rigidly secured to the bolsters, and it is to be noted in connection with both details of anchor that the longitudinally extending portions of the anchor walls rest in close proximity to the 105 inner faces of the center sills and substantially, though not entirely, fill the space between said center sills, said walls extending downwardly to a considerable distance below the tops of said center sills, so as to provide means to prevent tipping or rocking of the tank on its underframe. The wedges likewise also extend substantially from center sill to center sill, there being only such clearance between the wedge and the sills 110 as is necessary for convenient manipulation of the parts. Thus it will appear that the anchor forming the subject-matter of the present invention serves not only as a means to prevent longitudinal movement of the 115 tank independently of its underframe, but also prevents vertical separation of the tank and underframe and rocking of the tank.

It is well known that the center sills do not support the tank at the middle of its 120 length, but, on the contrary, the tank supports the middle portion of the sills, due to the fact that the tank is a strong tubular girder-like structure which is stiffer than the underlying sills of the underframe, and in 125 130

assembling tank cars it is commonly necessary to apply the central tank bands B—B and pull the sills upwardly to the tank. This is accomplished by the wedges of the 5 central anchor before referred to in the act of placing the wedge in its operative position.

When desired the wedge and its holding bolt may be carried by the stops rather than by the depending casting on the tank itself, 10 and the stop 6 in Fig. 3 has a transversely extending projecting overhang or head 19, supported by which head and depending therethrough are the bolts 15 supporting the casting 16, as hereinbefore described.

15 It is obvious that while two wedges have been shown with each car it is within the skill of a mechanic in view of this disclosure to incline one of the transverse walls 12 so as to fit the downward and rearward inclination of the abutting face 18 of the stop 6 and make use of one of the wedges 16 at the opposite end of the casting or car body, it being understood that the tank or car body is lowered into position between the stops, 20 and the driving of one of the wedges will force the inclined face at the opposite end into engagement with the inclined face of the stop.

What I claim is:

30 1. In a car, the combination with an underframe, fixed spaced stop members, of a car body anchor disposed between said stop members and spaced from and movable relatively thereto, the spaces between the members 35 being wider at the bottom than at the top, and a wedging element carried by one of said members adapted to be drawn into one of said spaces to lock the members together.

2. In a car, the combination with fixed 40 stop members, of a longitudinally movable car body anchor disposed between said stop members and limited in its movement in one direction by one of said stops, the space between the other stop and the car body anchor being wider at one place than at another place, and a wedge carried by one of 45 said members adapted to be drawn into said space to lock the members together.

3. The combination with an underframe, 50 of a tank supported thereby and removable therefrom without destructive effort, and a vertically movable wedge locking said tank to the underframe against separation in a vertical direction.

55 4. The combination of an underframe having a stop, of a car body, an anchor for said car body facing said stop, the facing surfaces of said stop and anchor being inclined relative to each other, and a member 60 adapted to be forced vertically between said stop and anchor.

5. The combination with spaced center sills having a plurality of spaced apart stops carried therebetween, of a tank having 65 an anchor attached thereto and depend-

ing therefrom between said center sills and between said stops, and a plurality of vertically movable locking means disposed between the stops and the adjacent parts of the anchor.

70 6. The combination with spaced center sills having interposed therebetween a plurality of spaced sill separating members serving as stops, of a car body, an anchor therefor depending therefrom between the 75 sills and between said stops and spaced from said stops, and a filling member disposed between one end of said anchor and the adjacent stop.

7. The combination with an underframe, 80 of a car body having a member depending therefrom into the underframe, and a vertically movable wedge disposed between the depending member and a part of the underframe and adapted to move said car body 85 relative to the underframe.

8. As a means for centering a tank on a car underframe, longitudinally spaced apart vertically movable wedges each disposed between a vertical element of the tank, and a 90 portion of the underframe.

9. In a car underframe, the combination with spaced center sills, fixed stops between said sills, of a body anchoring member disposed between said stops and movable relative thereto, and vertically movable means disposed between one of said stops and said member adapted to move said member toward the other of said stops.

95 10. The combination with an underframe, 100 including center sills, lugs carried between said sills, a car body, an anchor member depending from said body between said lugs and between said center sills, and a vertically movable member filling the space between one of said lugs and anchor.

11. The combination of center sills, a tank mounted thereabove, and a vertically movable wedge adapted to lock said tank to said sills.

110 12. In a car, spaced center sills, a plurality of spaced stops carried between said sills connecting said spaced sills, an anchor disposed between said stops, and a vertically movable wedge disposed between one of said 115 stops and the anchor.

13. In a car, center sills, a plurality of stops carried below the top plane of said sills, spaced longitudinally of said sills, an anchor disposed between said stops, a wedge 120 disposed between each stop and the anchor, and means for moving said wedges into engagement with the stop and anchor.

14. In a tank anchor for tank cars, the combination of a freely removable tank, a 125 fixed abutment and a juxtaposed vertically movable tank anchor co-operating with said abutment, one of said members having an inclined face, and a vertically movable interposed wedge.

15. The combination with an underframe, of a car body having a member depending therefrom into the underframe, and a vertically movable wedge disposed between the depending member and a part of the underframe and adapted to lock said car body in position on the underframe.

16. The combination of an underframe, a tank mounted thereon, an anchor depending from the tank near the middle of said underframe, and a vertically movable member coöperating with said underframe and anchor and adapted to lock the tank to the underframe.

15 17. The combination of an underframe, a tank mounted thereon, an anchor depending from the tank near the middle of said underframe, and a vertically movable member supported by said anchor adapted to lift the middle portion of the underframe.

20 18. In an anchorage device for the tanks of tank cars, a freely removable tank, an abut-

ment in the plane of the car underframe, an anchor depending from the tank and coöperating with the said abutment, and a vertically movable interposed wedge. 25

19. In a tank car an underframe, a tank removable therefrom without destructive effort, an anchor depending from the tank and vertically movable means coöperating therewith adapted to lock the tank to the underframe against vertical movement of tank or underframe. 30

20. In a tank anchor for tank cars a fixed anchor and a vertically movable wedge. 35

21. In a tank anchor for tank cars, a vertically movable wedge and means for moving said wedge.

In witness whereof I have hereunto set my hand in the presence of two witnesses. 40

GEORGE P. BENDER.
